UNITED STATES PATENT OFFICE

PHILIP S. KEARNEY, OF OXFORD, NORTH CAROLINA

RURAL MAIL-BOX SUPPORT

Application filed January 6, 1930. Serial No. 418,921

My invention relates to improvements in rural mail box supports.

In accordance with my invention, I provide a rural mail box support embodying a post to be set into the ground upon the far side of the ditch, at a suitable distance from the same, so that it will be out of the way and not struck by the road machine when the ditch is being scraped out or otherwise repaired. A generally horizontal arm is preferably freely removably mounted upon the post so that it may be separated therefrom and laid upon the ground upon the far side of the ditch when the road machine or the like is scraping out the ditch. When the arm is mounted upon the post, it is pivotally supported, and can swing generally horizontally in either direction, in limits. A flexible element is secured to the far end portion of the arm, and is connected with the post in such a manner that it will wind upon the post when the arm is swung in either direction. This winding of the flexible element upon the post serves to raise the near end portion of the arm as it is swung laterally in either direction, should the same be struck by a traveling vehicle upon the road, and due to this raising action, the arm will, when released, gravitate and return to the lowermost position, which is at a right angle to the longitudinal axis of the road. The arm is made sufficiently long whereby it extends over the ditch and slightly over the edge or shoulder of the road and the free end of the arm carries the mail box, so that the postman may have access to the box without driving into the ditch. The device is simple in construction, cheap to manufacture, strong and durable.

In the accompanying drawings, forming a part of this specification, and in which like numerals are employed to designate like parts throughout the same,

Figure 1 is a side elevation of a rural mail box support embodying my invention,

Figure 2 is a plan view of the same,

Figure 3 is a detailed longitudinal section taken on line 3—3 of Figure 2,

Figure 4 is a horizontal section taken on line 4—4 of Figure 1,

Figure 5 is a transverse section taken on line 5—5 of Figure 1,

Figure 6 is a horizontal section taken on line 6—6 of Figure 3, and,

Figure 7 is a vertical section taken on line 7—7 of Figure 3.

In the drawings, wherein for the purpose of illustration, is shown a preferred embodiment of my invention, the numeral 5 designates a road having a ditch 6 at its edge or shoulder.

The numeral 7 designates a post included in my rural mail box support. This post may be formed of wood, concrete or other suitable material. The post is preferably vertically arranged and is embedded in the ground upon the far side of the ditch 6, and suitably spaced from the ditch so that the post will not be struck by a road machine, in scraping out the ditch 6.

The numeral 8 designates an arm which is normally generally horizontally arranged and disposed at approximately a right angle to the longitudinal axes of the road 5. This arm may be formed of a wooden beam 9, which may be stiffened or reinforced by boards 10 nailed to the vertical edges of the same, these boards projecting downwardly beyond the beam 9, as shown. While I prefer to construct the arm 9 as above shown and described, yet the invention is not necessarily restricted to such construction, and I contemplate making the same of metal or of any other material.

A mail box 11 of any well known or preferred type is mounted upon the near end of the arm 8. As shown in Figure 1, the arm 8 extends across the ditch 6 and inwardly beyond the same, so that the mail box 11 is supported over the road adjacent to its edge or shoulder, thereby rendering it possible for the postman to have access to the mail box without driving into the ditch.

The beam 9, Figure 3, is provided at a point between its ends and nearer its far end with a recess 12, receiving a socket 13, having a flange 14, at its lower end, rigidly attached to the beam 9 by means of screws 15, or the like. This socket is generally elliptical in horizontal cross section and has a substan-

tially vertical near wall 16 and an inclined far wall 17, the wall 17 extending away from the wall 16 in a downwardly direction. The side walls 18 of the socket are vertical. For 5 co-action with the socket 13, I provide an upstanding pivot element or pin 19, preferably having its upper end rounded, and this pin extends into the socket 13, and is of such a diameter that its opposite sides substantially contact with the opposite side walls 18 of the socket. The pin 19 is cylindrical and is secured, at its lower end, to a base 20, which is rigidly attached to the top of the post 17, by any suitable means. The arm 8 is preferably held by the pivot element 19 at a suitable 15 elevation above the post 7, so that it will not strike with the post during its swinging action.

The numeral 21 designates a diagonal flexible element which may be in the form of a chain, cable or the like, and the upper end of this flexible element is attached to the far end of the arm 8 through the medium of an eye-bolt 22 or any other suitable fastening. 20 At its lower end, the flexible element 21 embodies a forked portion including flexible side elements 23, which diverge downwardly and are attached to the opposite sides of the post 7, as shown at 24, preferably at diametrically opposite points. It is thus seen that the flexible element 21 is so attached to the post that it will be wound thereon, when the arm 8 is swung laterally in either direction.

25 The operation of the support is as follows:

The arm 8 having its near end portion longer than the far end portion of the same, such near end portion carrying the mail box 11, gravitates to a normal central generally horizontal position, which is defined by the flexible element 21 and the vertical wall 16 engaging a pivot element 19. Should the arm 8 be struck by a vehicle traveling upon 40 the road, in either direction, the arm 8 will be swung in the corresponding direction, and one end portion of the flexible element 21 will be wound upon the post 7, causing the near end portion of the arm to swing upwardly 45 during its lateral movement. This upward swinging movement is rendered possible by the longitudinal elliptical shape of the socket 13, but when the pivot element 19 engages the inclined wall 17, the upward swinging movement is stopped. When the arm is released, it will gravitate to the lowermost central position and be retained in this position by gravity. When it is desired to remove the arm from the post, so that it will be out of 50 the way of the road machine scraping out the ditch or the like, such arm may be readily lifted from the pivot element 19 and may be laid upon the ground at the far side of the ditch, and, of course, may be readily returned to position upon the post. In remov-

ing the arm from the post, it is not necessary to separate the flexible element from the post or the arm.

It is to be understood that the form of my invention, herewith shown and described, is 70 to be taken as a preferred example of the same, and that various changes in the shape, size and arrangement of parts, may be resorted to without departing from the spirit 75 of my invention, or the scope of the subjoined claims.

Having thus described my invention, I claim:

1. A rural mail box support, comprising a 80 post, an arm pivotally mounted upon the post to swing horizontally and vertically, one end of the arm being adapted to carry a mail box, and a relatively non-extensible flexible element attached to the opposite end of the arm and secured to the post in such a manner that the flexible element will be wound upon the post when the arm is swung laterally in either direction, the winding action of the flexible element upon the post causing 85 the arm to swing vertically. 90

2. A rural mail box support, comprising a post, an arm, means for pivotally mounting the arm upon the post so that said arm is freely removable therefrom and is capable of swinging horizontally and vertically, and a relatively non-extensible flexible element attached to one end portion of the arm and secured to the post in such a manner that the flexible element is wound upon the post when the arm is swung laterally, the winding action 100 of the flexible element upon the post causing the arm to swing vertically, the opposite end portion of the arm being adapted to support a mail box. 105

3. A rural mail box support, comprising 110 a post, a pivot element carried by the post, a socket to receive the pivot element and having its lower end opened and its upper end closed, an arm carrying the socket, one end portion of the arm being adapted to support 115 a mail box, and a flexible element secured to the opposite end portion of the arm and connected to the post in such a manner that it will be wound upon the post when the arm is swung laterally. 120

4. A rural mail box support, comprising 125 a post, an upstanding pivot element carried by the post, an arm having one end adapted to support a mail box, a socket secured to the arm between the ends of the same, said socket having a bore which is generally elliptical providing a substantially vertical end wall and an inclined end wall, the socket being adapted to turn horizontally upon the pivot element and to swing vertically upon the same with the end walls limiting the vertical swinging movements, and a flexible element attached to the opposite end portion of the arm and having a forked portion embodying 130

flexible side elements which are secured to the opposite sides of the post, the arrangement being such that the flexible element is wound upon the post when the arm is swung laterally in either direction.

5 In testimony whereof I affix my signature.

PHILIP S. KEARNEY.
